Patented Mar. 5, 1968

210,348

HAIRBRUSH BACK OR SIMILAR ARTICLE

Monte Levin, New York, N.Y., assignor to Empire Brushes, Inc., Port Chester, N.Y., a corporation of New York

Filed Apr. 25, 1967, Ser. No. 6,826

Term of patent 14 years

(Cl. D4—31)

FIG. 5

FIG. 2

FIG. 1

FIG. 3

FIG. 4

FIG. 6

FIG. 7

FIG. 8

FIG. 9

FIG. 10

FIG. 11

FIG. 12

FIG. 13

FIG. 1 is a top view of a hairbrush back or similar article embodying the invention;

FIG. 2 is one side edge view thereof;

FIG. 3 is a side view of an opposite edge thereof;

FIG. 4 is a bottom view thereof;

FIG. 5 is a view of the front end thereof;

FIG. 6 is a view of the rear end thereof;

FIG. 7 is a cross-sectional view taken on line 7—7 of FIG. 1;

FIG. 8 is a cross-sectional view taken on line 8—8 of FIG. 1;

FIG. 9 is a cross-sectional view taken on line 9—9 of FIG. 1;

FIG. 10 is a cross-sectional view taken on line 10—10 of FIG. 1;

FIG. 11 is a cross-sectional view taken on line 11—11 of FIG. 1;

FIG. 12 is a cross-sectional view taken on line 12—12 of FIG. 1; and

FIG. 13 is a cross-sectional view taken on line 13—13 of FIG. 1.

I claim:

The ornamental design for a hairbrush back or similar article, substantially as shown.
